LOCK DISPLAY STAND

Adolf Schoepe, Anaheim, Calif., assignor to Kwik-set Locks, Inc., Anaheim, Calif., a corporation of California

Application May 14, 1949, Serial No. 2,647

Term of patent 14 years

(CL. D80—9)

To all whom it may concern:

Be it known, that I, Adolf Schoepe, a citizen of the United States, residing at Anaheim, in the county of Orange, State of California, have invented a new, original, and ornamental Design for a Lock Display Stand, of which the following is a specification, reference being had to the accompanying drawing, forming part thereof.

Fig. 1 is a perspective view of a lock display stand, showing my new design;

Fig. 2 is a top plan view;

Fig. 3 is a side elevational view, the opposite side being similar; and

Fig. 4 is a rear elevational view thereof.

The broken lines showing the lock in Fig. 1 are for illustrative purposes only.

I claim:

The ornamental design for a lock display stand, as shown and described.

ADOLF SCHOEPE.
